UNITED STATES PATENT OFFICE.

HOMER D. WILLIAMS AND WILLIAM AILEN, OF DUQUESNE, PENNSYLVANIA.

HOTBED-OPERATING MECHANISM.

1,117,615.

Specification of Letters Patent. Patented Nov. 17, 1914.

Application filed November 22, 1913. Serial No. 802,463.

To all whom it may concern:

Be it known that we, HOMER D. WILLIAMS and WILLIAM AILEN, both residents of Duquesne, in the county of Allegheny and State of Pennsylvania, have invented certain new and useful Improvements in Hotbed-Operating Mechanisms, of which the following is a specification.

Our invention relates to apparatus employed in handling and storing rolled metal bars and similar flexible materials of small cross section and relatively long length and while not limited to such uses, more particularly relates to apparatus known in the art as hot beds and used in handling and storing such materials during the time interval in which they are being cooled from the heated condition in which they are received from the finishing passes of a rolling mill.

One object of our invention is to provide a hot bed of the "creeping" type having novel means whereby the hot bed is actuated in handling and conveying materials delivered alongside the hot bed from one side to the other of the hot bed.

Another object of our invention is to provide a hot bed of improved construction having serrated or notched supporting bars arranged to transfer the materials being handled across the width of the hot bed by a step by step movement and having a supporting bar actuating mechanism in the use of which the materials are successively lifted and are moved from the notches of one set of supporting bars into those in another set of supporting bars, with the sets of bars alternately acting to receive and to lift the metal and co-acting to engage with and support the materials being transferred between each lifting operation.

A further object of our invention is to provide a hot bed having improved means for delivering the bars from the notched bars forming the hot bed and for collecting and assembling, in a group, the materials delivered from the hot bed, preparatory to being transferred to a delivery table on which the materials are carried lengthwise away from alongside the hot bed to a shear or place of storage.

Referring to the drawings forming part of this specification, Figure 1 is a plan showing a portion of a hot bed equipped with a hot bed operating mechanism constructed and arranged in accordance with our invention. Fig. 2 is a sectional end elevation

of the apparatus of Fig. 1. Fig. 3 is a detail sectional end elevation of the apparatus of Figs. 1 and 2. Fig. 4 is a detail sectional elevation on the line IV-IV of Fig. 3. Fig. 5 is a detail sectional plan, the section being taken on the line V-V of Fig. 3.

In the accompanying drawings, the numerals 2 and 3 designate serrated or notched conveyer bars which are mounted upon suitable longitudinal beams or girders 4-5 and 6-7 and are arranged to form independently movable sets. The notched conveyer bars 2 forming one set are mounted upon the beams or girders 4-5 and the notched conveyer bars 3 forming the other set are mounted upon the beams or girders 6-7.

The sets of beams 4 and 5 and 6 and 7 are secured to the ends of transversely extending rocking beams or supports 8 and 9, which are provided at intervals in the length of the hot bed, and are pivoted at their outer ends to one end of rocking arms 10. The supports 8 and 9 are mounted, at an intermediate point in their length, upon oppositely extending eccentrics 11 and 12 each of the beams 8 being mounted upon an eccentric 11 and the beams 9 on an eccentric 12. The eccentrics 11 and 12 are secured on or may form an integral part of the eccentric shaft 13 which extends lengthwise parallel to the length of the hot bed beneath the series of notched conveyer bars 2 and 3 and the shaft 13 is arranged to be intermittently rotated.

Center lines through the long diameters of the oppositely extending eccentrics 11 and 12 are in the same plane and when the sets of conveyer bars 2 and 3 are at rest, as is the case between the intermittent lifting movements of these bars, a center line through the center of the eccentric shaft and the long diameters of the eccentrics extends horizontally, so that in this way the hot bed is balanced.

The hot bed generally is very long (between 450 and 500 feet in this particular case) so that at times and when some kinds of materials are being rolled it is unnecessary to operate the entire length of the hot bed. In such cases jaw clutch couplings are employed at about the middle of the length of the eccentric shaft 13 which are arranged to be moved to disconnect one half from the driving mechanism and the other half of the length of the hot bed.

The clutch couplings are formed of a jaw

section 14 keyed or otherwise fastened to one section of the shaft 13 and a jaw section 15 fastened by a feather key to rotate with the adjacent section of this shaft having the driving gear 20 thereon and to slide on the shaft to move its jaws into and out of engagement with the jaws of the coupling members 14. Lever arms 16, 16 are secured on one end of clutch coupling operating shafts 17, 17^a which extend transversely beneath the conveyer bars and are pivoted at one end on brackets 17^b fastened to conveniently located bearings 18 for the shaft 13. The other end of the shafts 17, and 17^a project beyond through bearings 17^c at one side of the hot bed and are provided with upwardly extending coupling shifting levers 19 or 19^a by which the clutch couplings are actuated manually in connecting and disconnecting the clutch jaws 14, 14 and 15, 15 on the adjoining ends of the sections of the shaft 13.

Keyed or otherwise fastened to the middle section of the eccentric shaft 13 is a spur gear 20 which meshes with a larger spur gear 21 on the counter shaft 22. The ratio of the gear 21 to the gear 20 is as 2 to 1 so that with each half revolution of the eccentric shaft 13 the gear 21 must rotate one-quarter revolution. Each half revolution of the eccentric shaft 13 moves the long axis of each eccentric through an arc of 180 degrees, or from a horizontal position on one side of a vertical plane through the center of the shaft 13 into a horizontal position on the opposite side of such plane. Also fastened on each end of the counter-shaft 22 is a ratchet wheel 23 having four teeth equally spaced at angles of 90 degrees, the teeth of these ratchet wheels being operatively engaged by the ratchet pawls 24 pivotally mounted between the forks of the rocking arms forming the ratchet levers 25 which are pivoted at one end upon the ends of the shaft 22. The ratchet pawls 24 are connected to one end of ropes 26 or like flexible members which pass over the sheave wheels 27, 28 and 29 and each rope 26 has a counterweight 30 to yieldingly hold the swinging end of each ratchet pawl 24 in engagement with the periphery of its co-acting ratchet wheel 23.

Each swinging outer end of the ratchet levers 25 is pivotally connected to an end of one of the connecting rods 31, and the other ends of these rods 31 are pivotally connected to the crank pins 32 of the cranks 33 on the ends of the crank shaft 34. The crank shaft 34 is mounted to rotate in bearings 35, 35 on the base plate 36 and has a spur gear 37 meshing with the spur pinion 38 on the end of the motor countershaft 39 which is mounted in bearings 40, 40 forming part of the base plate 36. The countershaft 39 has a spur gear 41 meshing with the

driving pinion 42 on the end of the armature shaft 43 of the driving motor 44 which also is mounted on the base plate 36.

As shown in the drawings the notched conveyer bars forming the hot bed are located alongside a receiving table formed by the series of conoidal feed rollers 46, and on which the materials are transferred lengthwise alongside the hot bed from the rolling mill or other point of supply. The rollers 46 are each provided at one end with a rope groove 47 through which they are driven by contact with the endless driving rope 48, this rope which is driven in any desired manner engaging with diametrically opposite points in the grooves 47 in serving to drive the rollers 46 of the receiving table.

The receiving table formed by the feed rollers 46, is provided with apron plates 49 having inclined surfaces. These plates are located between the rollers 46 and the receiving ends of the conveyer bars 2 and 3 and are supported on the beams forming the sides of the receiving table supports. The lower edge or side of the apron plates 49 has an upwardly and outwardly inclined rib 50 forming stops for the materials supported on the apron plates 49. With the apron plates 49 arranged in this manner the materials slide down the inclined surface thereof against the stops 50 into position to be engaged and lifted by the conveyer bars 2 and 3 into the first set of notches in the notched conveyer bars.

As the bars or other materials are delivered by the inclined sides of the apron plates 49 in position to be lifted into the first set of notches in the conveyer bars 2 and 3, the shaft 13 is caused to rotate, which causes the eccentrics 11 and 12 to lift the inner ends of the beams 8 and 9 and, through the beams 4 and 5, and 6 and 7 lift the opposite ends of the supporting bars 2 and 3, one end of the series of bars in each set being raised by this operation. When this occurs, the materials resting on the hot bed will be engaged by the ends of the conveyer bars 2 and 3 and will be raised vertically and transferred sidewise thereby until above the adjacent set of notches in the other set of bars 3, and as the eccentrics 11 and 12 continue to rotate, the bars will be deposited alternately in successive sets of notches in the sets of conveyer bars 2 and 3. After each half revolution has been completed by the eccentrics the relative position of the bars 2 and 3 is changed the receiving set of notches becoming the lifting set, while the lifting set becomes the receiving set.

It should be noted that when the bars of both sets are parallel, the notches in one set are in alignment with those in the other set, and that the materials are supported by each of both sets of bars while in this position. It should also be noted that the con-

veyer bars are intermittently actuated and that they are brought to rest always with the notches in the upper edges thereof in the same horizontal plane.

5 On the second half of the revolution of the eccentrics, the materials are lifted by the notches in the other set of bars and are moved vertically and horizontally sidewise until they are above the next adjacent set 12 of notches in the lifting bars. Meanwhile a new lot of materials will when available, have been transferred from the feed table 19 rollers 46 and be deposited on the inclined apron plates 49.

15 The above described operations are continued as the materials are supplied to the hot bed by the receiving table. The notches in the sets of bars will become filled with materials and the materials are caused to move by a step by step movement across the length of the notched conveyer bars and are finally discharged upon the series of shuffle bars 51 and 52. These shuffle bars are arranged in two sets and are secured at one 25 end upon eccentrics 53 positioned at intervals in the length of hot bed on the eccentric shaft 54. The shuffle bars are supported on the opposite side of the delivery table formed by the delivery table rollers 55 upon 30 crank arms 56, the arms 56 being mounted upon the lifting shaft 57. The delivery table rollers 55 are operated preferably by means of a line shaft 58 and bevel gears 59, 60 driven by a suitable motor. (not shown) 35 which construction being old and well-known need not be further described. The eccentric shaft 54 is also connected to a driving motor (not shown) so as to be rotated either constantly or intermittently and the lifting shaft 57 is arranged to rock so as to swing the arms 56 from the position shown into an upright position. When so lifted the outer 40 ends of the series of shuffle bars 51, 52 will be raised until their upper edges extend above the plane of the top of the table rollers 55 and as the eccentrics 53 rotate, these shuffle bars alternately lift and thereby act to move materials collected thereon from the hot bed, until the materials are immediately 45 above the rollers 55. The shaft 57 which is operated by a suitable motor (not shown) is then swung to lower the crank arms 56 which causes the materials upon the shuffle bars to be transferred to the rollers 55. 50 These rollers are then rotated so as to transfer the materials thereon, endwise, from alongside the discharging side of the hot bed.

55 The advantages of our invention will be appreciated by those skilled in the art. By the novel construction shown and described, the bars are successively removed from a receiving table to the hot bed and the bars are then gradually moved by a step by step 60 movement across the width of the hot bed,

this movement being regulated preferably by the time necessary to allow such bars to become cool and the materials are supported by each of the sets of conveyer bars between successive lifting operations. After the materials are transferred across the width of the hot bed, they are collected in groups and the grouped materials are then transferred bodily sidewise without any sliding movement and are deposited on the feed rollers 70 of a receiving table by which they are afterward transferred lengthwise to a place of disposal of such materials. 75

Modifications in the construction and arrangement of the parts may be made within 80 the scope of our invention.

We claim:

1. A hot bed comprising a plurality of conveyer bars arranged in independently lifting sets, mechanism for moving said sets 85 of bars to alternately engage and lift materials supported thereon in transferring the materials across the width of said hot bed, and means for intermittently actuating said moving mechanism, said means being 90 adapted to stop the conveyer bars between lifting movements thereof, with the upper edges of said bars in supporting engagement with the materials being transferred. 95

2. A hot bed comprising a plurality of 95 conveyer bars arranged in independently lifting sets, mechanism for moving said sets of bars to alternately engage and lift materials supported thereon in transferring the materials across the width of said hot 100 bed, and means for intermittently actuating said moving mechanism said means being adapted to stop the conveyer bars between lifting movements thereof and bring the upper edges of said bars in the same plane. 105

3. A hot bed comprising a plurality of notched or serrated conveyer bars arranged in independently lifting sets, mechanism for moving said sets of bars to alternately engage and lift materials supported thereon in transferring the materials across the width of said hot bed, and means for intermittently actuating said moving mechanism, said means being adapted to stop the conveyer bars between lifting movements 110 thereof with the inclined edges of the notches or serrations in alinement. 115

4. A hot bed comprising a plurality of notched or serrated conveyer bars arranged in independently lifting sets, mechanism 120 for moving said sets of bars to alternately engage and lift materials supported thereon in transferring the materials across the width of said hot bed, and means for intermittently actuating said moving mechanism, said means being adapted to stop the conveyer bars between lifting movements 125 thereof with the inclined edges of the notches or serrations in the same plane.

5. A hot bed comprising a plurality of 130

conveyer bars arranged in independently lifting sets means on which said sets of bars are pivotally mounted, one set of the bars being pivotally supported at the opposite side of the hot bed to that of the other, an eccentric shaft having oppositely extending eccentrics thereon engaging with said sets of bars and means for rotating said shaft, said last named means operating intermittently and bringing the eccentrics to rest with a center line on their long diameter extending horizontally.

6. In a hot bed the combination with a series of conveyer bars arranged in alternately lifting sets and an eccentric shaft by which said bars are actuated, of a shaft driving mechanism arranged to intermittently actuate the shaft, said mechanism moving the bars to bring the upper edges thereby into alinement at the end of each intermittent movement of the eccentric shaft.

7. In a hot bed the combination with a series of conveyer bars arranged in alternately lifting sets, and an eccentric shaft having oppositely extending eccentrics engaging with and lifting the sets of bars, of

a shaft driving mechanism comprising a ratchet wheel operatively connected to the eccentric shaft a swinging arm having a pawl operatively engaging with the ratchet wheel and means for swinging said arm to intermittently move the ratchet wheel and rotate the eccentric shaft.

8. In a hot bed the combination with a series of conveyer bars arranged in alternately lifting sets, and an eccentric shaft having oppositely extending eccentrics engaging with and lifting the sets of bars, of a shaft driving mechanism comprising a ratchet wheel operatively connected to the eccentric shaft, a swinging arm having a pawl operatively engaging with the ratchet wheel and a rotary motor for actuating said swinging arm to intermittently move the ratchet wheel to rotate the eccentric shaft.

In testimony whereof, we have hereunto set our hands.

HOMER D. WILLIAMS.
WILLIAM AHLEN.
